(57) **CLAIM**

The ornamental design for a rear suspension for motorcycles, as shown and described.

DESCRIPTION

FIG. 1 is a left side elevational view of a rear suspension for motorcycles showing our new design;

FIG. 2 is a front left perspective view thereof;

FIG. 3 is an enlarged left side elevational view of the rear suspension for motorcycles of a portion of FIG. 1; and, FIG. 4 is an enlarged left side perspective view of the rear suspension for motorcycles of a portion of FIG. 2.

The faded out or overexposed showing of portions of the motorcycle are provided for the purpose of illustrating environmental structure and forms no part of the claimed design.

The circular dotted lines in FIGS. 1 and 2 are only reference bubbles showing the area of enlargement depicted in FIGS. 3 and 4.

The broken lines at the upper right side portions of the rear suspension in FIGS. 3 and 4 are design features of the claimed design.

1 Claim, 4 Drawing Sheets Fig. 2
